CLAIM

The ornamental design for a display screen with interface for geo-networking website; as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen with interface for geo-networking web site showing my new design;

FIG. 2 is a front view of a second image thereof;

FIG. 3 is a front view of the user interface having a third image thereof; and,

FIG. 4 is a front view of the user interface having a fourth image thereof.

The broken line showing of a display screen or portion thereof and graphical elements within the display screen are not part of the claimed design.

The appearance of the transitional image sequentially transitions between the images shown in FIGS. 1-4. The process or period in which one image transitions to another forms no part of the claimed design.
